UNITED STATES PATENT OFFICE.

JOHN SIGWALT AND ARTHUR M. WILLARD, OF CHICAGO, ILLINOIS.

DESIGN FOR A HAND-SEAL-PRESS BODY.

SPECIFICATION forming part of Design No. 37,158, dated September 27, 1904.

Application filed July 5, 1904. Serial No. 215,411. Term of patent 14 years.

To all whom it may concern:

Be it known that we, JOHN SIGWALT and ARTHUR M. WILLARD, citizens of the United States, residing at Chicago, in the county of Cook and State of Illinois, have invented a new, original, and ornamental Design for a Hand-Seal-Press Body, of which the following is a specification, reference being had to the accompanying drawings, forming part thereof.

Figures 1 and 2 are perspective view and

front elevation, respectively, of a hand-seal-press body, showing our design.

We claim as new and desire to secure by Letters Patent—

The ornamental design for a hand-seal-press body as shown.

JOHN SIGWALT.

ARTHUR M. WILLARD.
